UNITED STATES PATENT OFFICE.

HENRY H. HANTON, OF LANCASTER, PENNSYLVANIA, ASSIGNOR TO FRAIM-SLAY-MAKER HARDWARE CO., INC., OF LANCASTER, PENNSYLVANIA, A CORPORATION OF PENNSYLVANIA.

PADLOCK.

Application filed December 8, 1925. Serial No. 74,154.

This invention relates to locks, and more particularly to padlocks of the safety or thief-proof type having a chain attached for securing various articles so that they may not be easily stolen, for example, by locking together the two ends of the chain which may embrace an automobile spare tire or other article to be secured against theft.

It is common practice to secure one end of a chain to a padlock for various uses to which such locks with a chain attached may be put, especially for out door heavy duty requirements, by securing one end of a chain to a clevis-like device adapted to embrace a link of the chain and then riveting such device to the shackle, or to a lug or projection formed integrally with the case, or by securing the two limbs of the clevis-like device with the chain attached in a recess in the case when the several parts are assembled and riveted together; all of which operations are more or less expensive and increase the cost of manufacture.

The objects of my invention are to provide a padlock with a shackle which will serve as a means for attaching thereto one end of a chain which may be passed around an article to be secured against theft by locking together the two ends of the chain, thus dispensing with the clevis-like devices and riveting means heretofore employed for securing a chain to a padlock, and reducing the cost of manufacture of padlocks with a chain attached while producing a highly useful and durable theft-proof device for the purposes mentioned.

The invention will first be hereinafter more particularly described, with reference to the accompanying drawings, which are to be taken as a part of this specification, and then pointed out in the claims at the end of the description.

In said drawings, Fig. 1 represents a sectional side elevation of a padlock embodying my invention, showing fragmentary portions of two ends of a chain locked together;

Fig. 2 is a side elevation of the same;

Fig. 3 is a side elevation of the padlock with the shackle unlocked and thrown back

into position to either release or connect the free end of a chain therewith; one end of a chain being permanently secured thereto; and

Fig. 4 is a detail view showing in full lines the bendable lug on the inner side of the main body portion of the shackle between which and one limb of the shackle one end of a chain is permanently secured, as shown in Figs. 1 and 3, by bending said lug toward the adjacent limb; the form of the lug after bending being indicated in dotted lines.

Referring to said drawings, in which the same reference letters are used to denote corresponding parts in different views, the letter A may denote a padlock case, which may be of the form shown or any suitable construction. It has pivoted thereto a shackle B of yoke-like form, with depending limbs b, b¹ and intermediate lugs b² and b³ for a purpose hereinafter described. The limb b of the yoke is fitted in a recess provided therefor at one side of the case between the two side plates or members a and a¹, which are secured together by riveting as usual when all the parts are properly assembled, and the limb b is pivotally secured in said recess by means of a pin or rivet c, while the free end portion or limb b¹ is provided with a notch c¹ to receive an interlocking part of an ordinary spring-pressed locking device within the case with which the shackle arm contacts when pressed into the case so as to cause said device to recede and permit the limb of the shackle to enter the case for engagement of the notch therein with said interlocking device, whereby the shackle will be firmly locked to the case by contact of said interlocking part with the shoulder formed at the base of said notch. The case and the locking mechanism contained therein may be of any suitable construction, such as commonly used in the construction of padlocks, in which a key is adapted to be inserted in a key-hole a¹ for retracting the spring-pressed locking device to disengage the shackle in a well known manner, said key-hole having a swinging cover a². Inasmuch as no claim is made

herein to the case or to the locking mechanism per se, no further description of the case or the locking mechanism therein appears to be necessary. The shackle is so formed as to leave as little space as possible between it and the case for the insertion of a jimmy or other tool for prying the lock open. It may be either round, oval or square in cross-section and it may be cast or otherwise formed out of any suitable metal, such as brass, bronze, malleable iron or steel. The lugs b^2 and b^3 on the lower or inner side of the main body portion of the shackle provide a suitable recess between each lug and the adjacent limb of the shackle for the link of a chain to snugly fit therein, and the lug at the right or adjacent the pivoted end of the shackle is long enough to adapt it to be swaged or bent back over the chain link, as shown, so as to permanently secure one end of the chain to the shackle and prevent the chain from becoming detached without applying sufficient force to break or overcome the binding force of the bendable lug.

A lock of the described construction is especially designed for use in locking together the two ends of a chain embracing an automobile tire or other article to be secured to a fixture so that the article cannot be stolen, but it is not limited in its application to any particular use, and it may be used for various purposes and in different relations, wherever it is desired to use a padlock with a chain attached, especially for all out door heavy duty requirements, where padlocks are adapted to be used.

Having thus described my invention, what I claim as new and desire to secure by Letters Patent of the United States is:

1. In combination with a padlock having a case provided with suitable locking mechanism therein, a shackle of yoke-like form having one of its limbs pivoted at one side of the case and the other limb free and provided with means for interlocking engagement with said mechanism; the main body portion of the shackle having a pendant lug beside each limb arranged to provide a recess to receive a chain link between it and the adjacent limb, so that the two ends of the chain may be locked together; one lug being extended and adapted to be bent toward the adjacent limb of the yoke, so as to permanently secure one end of the chain thereto; the free end of the chain being adapted to be engaged with the other recess and locked therein when the free end of the shackle is locked within the case.

2. In combination with a padlock having a case provided with suitable locking mechanism therein, a shackle of yoke-like form having one of its limbs pivoted at one side of the case and the other limb provided with

means for interlocking engagement with said mechanism; the main body portion of the shackle having a pendant lug beside each limb arranged to provide a recess to receive and confine between it and the adjacent limb a link at one end of a chain; a lug being bent over toward the adjacent limb of the yoke so as to permanently secure one end of the chain thereto; the other end of the chain being free and adapted to be engaged with the other recess so that the two ends of the chain may be locked together when the free end of the shackle is locked within the case.

3. A padlock comprising a case containing a suitable device for locking engagement with a shackle, and a shackle of yoke-like form having one limb of the yoke pivoted to the case and the other limb constructed for interlocking engagement with the locking device within the case; the main body portion of the yoke being arranged in close proximity to the case and having pendant lugs thereon each spaced from one limb so as to provide a recess to receive a chain link between each lug and the adjacent limb of the yoke; one of said lugs being longer than the other and adapted to be bent toward the adjacent limb of the yoke for securing one end of a chain thereto while the other end of the chain is left free and adapted to engage the other recess and to be locked to the case by locking the free end of the shackle within the case.

4. A padlock comprising a case containing a suitable device for locking engagement with a shackle, and a shackle of yoke-like form having one limb of the yoke pivoted to the case and the other limb constructed for interlocking engagement with the locking device within the case; the main body portion of the yoke being arranged in close proximity to the case and having pendant lugs thereon each spaced from one limb so as to provide a recess to receive and confine a chain link between each lug and the adjacent limb of the yoke; one of said lugs being longer than the other and adapted to be bent toward the adjacent limb of the yoke for securing one end of a chain thereto, and a chain having a link at one end fitted in the recess adjacent the longer lug, the latter being bent over so as to partially close the recess and permanently secure one end of the chain to the shackle; the other end of the chain being free and adapted to engage the other recess and to be locked to the case by locking the free end of the shackle within the case.

5. In combination with a padlock having a case containing a retractable locking device adapted to engage and lock a limb of a shackle inserted therein, a shackle having two substantially parallel limbs and pendant

lugs therebetween forming a recess between each limb and an adjacent lug to receive a chain link; one of said lugs being bent toward the adjacent limb so as to permanently secure one end of the chain to the shackle while the other end of the chain is free and adapted to releasably engage one of

said recesses and to be locked therein when the shackle is inserted in the case; one limb of the shackle having means thereon for interlocking engagement with said locking device when inserted in the case. 10

In testimony whereof I affix my signature.

HENRY H. HANTON.
